Specification for Design.

Patented May 31, 1921.

Application filed November 20, 1920. Serial No. 425,563. Term of patent 7 years.

To all whom it may concern:

Be it known that I, CHARLES J. KERN, a citizen of the United States, residing at Buffalo, in the county of Erie and State of New York, have invented a new, original, and ornamental Design for Doll-Wagons, of which the following is a specification, reference being had to the accompanying drawing, forming part thereof.

The figure is a perspective view of a doll-wagon, showing my new design.

I claim:

The ornamental design for a doll-wagon, as shown.

In testimony whereof, I affix my signature.

CHARLES J. KERN.
